UNITED STATES PATENT OFFICE

2,510,435

VEGETABLE AND FRUIT SLICER

Edward J. Toman, San Bernardino, Calif.

Application February 9, 1948, Serial No. 7,027

6 Claims. (Cl. 146—114)

1

This invention relates generally to slicing machines, and more particularly to a slicer for vegetables and fruits.

In food slicers developed heretofore, the material is usually fed to either reciprocating or rotary knives from one side thereof and the slices of material are allowed to fall from the other side of the cutting element. In the instant invention the unsliced material is fed through a gauge plate into a rapidly revolving hollow cone equipped with veins to carry the material therewith while allowing the material to move eccentrically and toward the base of the cone, and a pair of rotary slicer discs are mounted in spaced coplanar relationship with the axes thereof parallel to the axis of the revolving cone. The configuration of the gauge plate and the dimensioning of the various elements is such that the material carried by the revolving cone is eventually reversed in its direction of movement and is brought into engagement with the rotary slicer discs from the sides thereof remote from the gauge plate through which the material originally entered, and positioning of the gauge plate relative to the discs allows the thickness of the slices to be varied.

With the above brief description of this invention in mind, the primary object of this invention will be understood to be the provision of a slicer which can be used to slice material such as vegetables and fruits at a very high rate of speed so that the slicer is particularly well adapted for use in commercial establishments such as canneries and the like.

Another object of this invention is to provide a food slicer which can be manufactured in small sizes for domestic use.

Still another object of this invention is to provide a slicer operating upon a novel principle implemented in such a manner that jamming of the slicer is practically made impossible, while the uniformity of the actual slicing operation is greater than that achieved by other slicing machines.

Another object of this invention is to provide a slicer which has relatively few moving parts, which is easily maintained and serviced and which is easily cleaned.

And a last object to be mentioned specifically is to provide a slicer which is relatively inexpensive and practicable to manufacture, which is safe and simple to use, and which will give generally efficient and durable service.

With these objects definitely in view, this invention resides in certain novel features of con-

2

struction, combination and arrangement of elements and portions as will be hereinafter described in the specification, particularly pointed out in the appended claims, and illustrated in the accompanying drawings which form a material part of this application, and in which:

Figure 1 is a three dimensional view of the assembled slicer;

10 Figure 2 is a front end elevational view of the slicer with the front end cover plate removed, to facilitate the illustration of the general arrangement of the elements of this invention;

15 Figure 3 is a view of this invention, largely in top plan, but showing the cone and portions of the casing in horizontal section, while the feed chute is represented in dash line;

Figure 4 is a longitudinal vertical sectional view, with portions of the bearings and the feed chute being shown in side elevation;

20 Figure 5 is a three dimensional view of the hollow feeder cone and the drive shaft therefor;

Figure 6 is a horizontal sectional view, designed to show particularly the structure making the gauge plate adjustable, the view being taken substantially on the irregular section line 6—6 in Figure 2, and portions of the supporting webs and the gauge plate being shown in plan; and

Figure 7 is a vertical sectional view, taken on a plane including the line 7—7 in Figure 6.

Similar characters of reference designate similar or identical elements and portions throughout the specification and throughout the several views of the drawings.

Referring now to the drawings in detail, it is proposed in this invention to provide a frame of suitable character which may include a pair of channel irons 10, a complement of suitable cross braces 12, and a trestle 14. Electric motors 16 and 18 are mounted upon this frame, the motor 18 being preferably adjustably mounted on the trestle 14 as indicated at 20. The frame also supports a pair of bearings 22, one or both of which may be of thrust bearing type, and the drive shaft 24 of the electric motor 16 is journaled in these bearings. At what will be considered the front end of the drive shaft 24 a suitable arbor member 26 is used to mount the hollow substantially conical feeder cone 28, as best indicated in Figures 3 and 4. This cone has an attachment boss 30 and what will be termed the base 32 of the cone revolves within an aperture in the vertical rear wall 34 of the casing or shield 36. In this connection, it may here be noted that this shield 36 has a removable panel

50 38 which is illustrated as reinforced with angle

55 38 which is illustrated as reinforced with angle

irons 40 and hinged to the main body portion of the shield by means of a hinge pin 42 slidably supported in brackets 44 on the panel. It may also be here noted that the shield 36 is open at the bottom as indicated at 46.

The cone 28 has a plurality of vanes 48 secured to the inner surface thereof by integral flanges 50 and bolts 52, the purpose of these vanes being made clear hereinafter. A pair of slicer discs 54 are mounted on short shafts 56 which are, in turn, journaled in elongated bearings 58 supported on a transverse plate member 60 of the frame, whereby these slicer discs are held in co-planar relationship and spaced apart so that portions 62 of the discs extend within the periphery of the said base.

A gauge plate 64 is adjustably mounted on a horizontal supporting plate 65 which is bolted to the transverse plate member 60, as indicated at 66. The gauge plate 64 is apertured centrally and is provided with a neck 68 and web members 70 which will ordinarily be integral with the vertical portion of the gauge plate and with the base flange 72 whereby the gauge plate is adjustably mounted on the plate 65. It will be noted that the flange member 72 is apertured as at 74 to receive a cam 76 carried on a short shaft 78 terminating at its upper end in the knob 80 and secured by a washer and nut 82 for manual rotation so that the cam 76 will urge the gauge plate toward and away from the portions 62 of the rotary discs 54. An index member or hand 84 may be carried by the knob 80 or shaft 78, cooperating with a graduated scale 86 on the upper surface of the flange member 72, so that the positioning of the gauge plate is clearly indicated to the operator of the machine.

The neck 68 of the gauge plate has secured thereto as at 88 the lower end of a feeder chute 88, and the panel 38 is apertured as at 90 to receive a portion of the feeder chute. The feeder chute and the gauge plate move as a unit when adjustment of the gauge plate is made. It is very important to note that the gauge plate 64 is laterally recessed at 92 to clear the discs 54, and a pair of laterally disposed clamping bolts 94 are used to clamp the gauge plate in position after adjustment has been made by the knob 80, and a pair of lateral guide rails 96 are secured to the sides of the plate 64 to retain the gauge plate in proper alignment when the clamping bolts 94 are released as during an adjustment of the gauge plate.

The operation of this invention will be clearly understood from the foregoing description of the mechanical details thereof, taken in connection with the above recitation of the objects sought to be achieved by this invention. Vegetables or fruit, generally indicated by the numeral 98 in Figure 4, will be fed through the feeder chute 88 and through the gauge plate 64 for passage between the rotary discs 54 into the rotating feeder cone 28. The material illustrated at 98 will then be carried outwardly by centrifugal action and will be reversed or moved toward the discs 54, sliding along the vanes 48 and outwardly along the inclined surfaces of the said cone, until contact is made with the side of the gauge plate 64 adjacent to the discs 54. Obviously, this construction allows for accurate adjustment, large capacity and extremely expeditious processing of fruits and vegetables and the like and the objects recited above are amply achieved.

Minor variations may be made in the exact 75

construction and proportionment of the elements of this invention without departure from the spirit and scope of this invention, which scope should be determined only by a proper interpretation of the terminology used in the subjoined claims.

Having thus described the invention, what is claimed as new is:

1. A slicer comprising a base, slicing discs rotatively mounted in spaced co-planar relationship transversely of said base, a hollow feeder cone rotatively mounted on said base with the axis of rotation of the cone parallel to and between the axes of rotation of said slicer discs, the base of said cone extending over adjacent portions of said discs, a gauge plate mounted transversely on said base for adjustment longitudinally thereof and on the side of said portions remote from said cone, said gauge plate having a central aperture, a feed chute leading into said aperture, and power means to rotate said discs and said cone.

2. A slicer comprising a base, slicing discs rotatively mounted in spaced co-planar relationship transversely of said base, a hollow feeder cone rotatively mounted on said base with the axis of rotation of the cone parallel to and between the axes of rotation of said slicer discs, the base of said cone extending over adjacent portions of said discs, a gauge plate mounted transversely on said base for adjustment longitudinally thereof and on the side of said portions remote from said cone, said gauge plate having a central aperture, a feed chute leading into said aperture, and power means to rotate said discs and said cone, said gauge plate being arcuately recessed on each side, and said discs having said first mentioned adjacent portions registering within said recesses.

3. A slicer comprising a base, slicing discs rotatively mounted in spaced co-planar relationship transversely of said base, a hollow feeder cone rotatively mounted on said base with the axis of rotation of the cone parallel to and between the axes of rotation of said slicer discs, the base of said cone extending over adjacent portions of said discs, a gauge plate mounted transversely on said base for adjustment longitudinally thereof and on the side of said portions remote from said cone, said gauge plate having a central aperture, a feed chute leading into said aperture, and power means to rotate said discs and said cone, said gauge plate being arcuately recessed on each side, and said discs having said first mentioned adjacent portions registering within said recesses, said cone having vanes secured internally thereon to prevent material from rotational movement relative to said cone.

4. A slicer comprising a base, slicing discs rotatively mounted in spaced co-planar relationship transversely of said base, a hollow feeder cone rotatively mounted on said base with the axis of rotation of the cone parallel to and between the axes of rotation of said slicer discs, the base of said cone extending over adjacent portions of said discs, a gauge plate mounted transversely on said base for adjustment longitudinally thereof and on the side of said portions remote from said cone, said gauge plate having a central aperture, a feed chute leading into said aperture, power means to rotate said discs and said cone, and a shield covering said slicer discs and having an open bottom.

5. A continuous feed slicer including a pair

of spaced co-planar revolving slicer discs, a gauge plate on one side of said discs and laterally recessed to register with edge portions of the discs, said gauge plate having a central aperture, a feeder chute leading into said aperture from the side of the gauge plate remote from the cone, a revolving hollow cone having its base opening on the other side of said discs and adjacent said portions whereby a continuous stream of heteromorphic material to be sliced is directed through said chute and aperture into said cone, said discs and gauge plate being substantially co-planar and together covering the base of said hollow cone.

6. A continuous feed slicer including a revolving slicer disc, a gauge plate on one side of said disc and laterally recessed to register with an edge portion of the disc, said gauge plate having an aperture, a feeder chute leading into said aperture from the side of the gauge plate remote from the cone, a revolving hollow cone having

its base opening on the other side of said disc adjacent said portion, whereby a continuous stream of heteromorphic material to be sliced is directed through said chute and aperture into said cone, and vanes on the interior surface of said cone to carry said material therewith, said vanes having co-planar edge portions adjacent said gauge plate, said disc and gauge plate being substantially co-planar and together covering

10 the base of said hollow cone.

EDWARD J. TOMAN.
